JOINER LINK

Charles Donda, Chicago, Ill., assignor to S. G. Taylor Chain Company, Hammond, Ind., a corporation of Illinois

Application February 21, 1948, Serial No. 10,050

3 Claims. (Cl. 59—85)

1

This invention has to do with improvements in joiner links, a joiner link being an open chain link provided with means for bridging the gap thereof when the chain is in use, but adapted to enable the link to be opened for the purpose of coupling the same to one or more closed links or to the eye of a hook or other load-handling equipment.

The principal object is to devise a joiner link which, while meeting all the fundamental requisites of an acceptable item of that character, such as complete dependability and susceptibility of being quickly and easily opened and closed, is, in addition, capable of being produced at minimum cost.

A cardinal feature of my improved joiner link is that the gap of the open link is bridged by a pair of complementary tie members, substantially identical, which are disposed oppositely at either side of the link and operate conjointly to embrace the two end portions of the link. Typically and preferably the two tie members are secured in clamping engagement with the link by means of a socket-head screw which can easily and quickly be removed and replaced for the purpose of opening and closing the link; and the tie members preferably are recessed at each end to form pockets in which the respective end portions of the links are nested.

The link and tie members are so designed that the load is transmitted therebetween through what may appropriately be termed a shear coupling; and this is accomplished most conveniently by providing the end portions of the link with laterally extending integral lugs which engage recesses or apertures formed in the tie members and closely fitting said lugs.

The outstanding advantage inherent in the above-outlined construction lies in the fact that both the link and the tie members can be forged so accurately that subsequent machining and dressing operations are reduced almost to insignificance.

Another feature of my invention, which is particularly applicable to large joiner links, resides in the fact that the laterally projecting lugs on each end portion of the link may be staggered lengthwise of the link, thereby facilitating attachment of relatively small closed chain links which might not be attachable to the joiner link if the lugs on each end portion thereof were disposed co-axially.

Other objects and features of my invention will be brought out as the ensuing detailed description progresses.

2

In the accompanying drawings:

Fig. 1 is an elevational view of a chain hitch including four joiner links in accordance with the subject invention and illustrating a typical application of the same;

Fig. 2 is an elevational view of a joiner link, illustrating a preferred embodiment of the invention, a portion of one of the tie members being broken off in this view for the purpose of more clearly depicting the internal construction;

Fig. 3 is an exploded view showing the several components of the joiner link of Fig. 2 in perspective;

Fig. 4 is a fragmentary detail view illustrating how the staggered arrangement of the laterally projecting lugs better enables attachment of small closed chain links to the joiner link;

Fig. 5 is an elevational view illustrating a modification or alternative embodiment of the invention; and

Fig. 6 is a transverse section taken at line 6—6 of Fig. 5.

The chain hitch illustrated in Fig. 1 comprises a relatively large closed link or loop 10 adapted to be hung on a derrick or crane hook, not shown, and having attached to it a pair of identical short chains 11 terminating at their lower ends in hooks 12 each having an eye portion 12a.

The chains 11 each consist of any convenient number of articulated closed links 13 and two joiner links 14, one at each end designed to facilitate attachment of said chains to the loop 10 and the hooks 12. The use of joiner links makes it convenient to substitute chains 11 of various lengths from time to time, as the need arises, and to add and subtract the number of chains attached to loop 10.

Because the need for such alterations may arise rather frequently, it is important that the joiner links be susceptible of being opened and closed quickly and easily; and it is, of course, even more important that the joiner links be safe and dependable.

The improved joiner link depicted in Figs. 2-4 comprises an open link 17, the ends 18 and 19 of which are separated by a gap 20, and a pair of tie members 21 and 22 which are secured together by a socket screw 23 in clamping engagement with the two end portions of link 17. Each end portion of said link is curved inwardly to conform generally with the curvature of the tie member and thereby provides the required lengths to accommodate two lugs 25 and 26 which are spaced apart and extend laterally from opposite sides 55 of the link.

Each of the two tie members 21 and 22 is preferably a forging of generally crescent configuration having in each end a recess 28, 29, formed to receive and fit one curved end portion of the link. Recesses 28 and 29 of each tie member register with corresponding recesses in the other tie member to form pockets in which the two end portions of the link are snugly nested; and the walls of said pockets are apertured as at 30 and 31 to receive the lugs 25 and 26.

The two tie members are rounded externally so as to provide suitably curved surfaces for contacting the chain links or rings bearing thereon, but the contiguous faces 33 of said tie members are flat and may bear against each other or be slightly spaced apart.

The two tie members 21 and 22 are nearly identical and differ only in that one of them has a tapped hole 34 designed to engage the thread of screw 23, while the other is provided with a counterbored hole 35 adapted to clear the shank of said screw and to receive and form a seat for the head thereof.

As previously stated, the principal reason for staggering lugs 25 and 26 is to make it possible to attach to the joiner link relatively small closed chain links which could not be passed over either end of the link if the lugs were disposed coaxially. This is adequately illustrated in Fig. 4 wherein there is shown a small closed chain link 36 in the process of being threaded on to one leg of the link 17. It will be self evident from the illustration that link 36 can easily be manipulated past the staggered lugs 25 and 26 whereas there would not be sufficient clearance if the two lugs were placed in axial alignment. Moreover, it will be apparent that even smaller link 36 than that shown can be passed over the staggered lugs.

For smaller joiner links and even for large ones where the necessity of attaching small links does not obtain, the modified construction illustrated in Figs. 5 and 6 can be utilized. Here, the open link 40 differs from the previously described open link 17 principally in that the laterally projecting lugs 41 and 42 at each end are situated in axial alignment. The two tie members 43 and 44 are, in substance, the same as the previously described tie members 21 and 22, and they are secured together by a socket screw 45 corresponding to previously described socket screw 23.

It will be seen that, in conformity with the previously stated object, the subject invention provides a joiner link construction which is exceedingly economical to manufacture, by reason of the slight amount of machining required, while entailing no sacrifice from the standpoint of strength and dependability or from the standpoint of the quickness and ease with which the link can be opened and closed.

While I have shown, by way of example, only two of the preferred embodiments of my invention, it will be obvious to those skilled in the art that there are numerous possible modifications and alternatives within the purview of my inventive concept and, accordingly, I do not wish to be limited otherwise than as indicated by the terms of the appended claims.

I claim:

1. The combination with an open chain link, of a pair of complementary tie members disposed oppositely at either side of said link and each bridging the gap between the ends of the link, each of said tie members being recessed at each end to form pockets for reception of the end portions of said link, said tie members conjointly embracing the two end portions of the link and each pocket of the tie members being formed with an orifice opening laterally through a side wall of the pocket, each end portion of said link having at least two laterally projecting portions, each extending through one of said orifices and in shear relation to the tie member in which such orifice is formed, individually, and means for detachably securing said tie members in clamping engagement with said link.
2. The combination with an open chain link, the open ends of which are curved toward each other, of a pair of complementary tie members disposed oppositely at either side of said link and each bridging the gap between the ends of the link, each of said tie members being recessed at each end to form curved pockets for reception of the curved end portions of said link, said tie members conjointly embracing the two end portions of the link and each curved pocket being formed with an orifice opening laterally through a side wall of the tie member, each end portion of said link having a pair of integral laterally extending lugs, the lugs of each pair being staggered on opposite sides of the link and positioned to extend through the orifices formed in opposing pockets of said tie members and in shear relation to the tie member in which such orifice is formed, and means for detachably securing said tie members in clamping engagement with said link.
3. In combination, an open chain link, each end portion of which is curved toward the other end and has a pair of laterally projecting lugs, the lugs of each pair being located on opposite sides of the link and in staggered relation lengthwise of the link, a pair of complementary tie members disposed oppositely at either side of said link and each bridging the gap between the ends of the link, each of said tie members overlapping the two end portions of the link and each recessed at both ends to form pockets in which the end portions of the link are nested, each said tie member being apertured near each end to engage, in shear relation, a lug on each end portion of the link, and screw means securing said tie members in clamping engagement with said link.
